HYDRAULIC SYSTEM

Albert Rivington Stone, Anneslie, Md.

Application May 17, 1945, Serial No. 594,279

9 Claims. (Cl. 60—97)

1

My invention relates to multiple hydraulic power units, and particularly concerns the control of such units under widely varying load demands when a constant speed, constant output source of pressure fluid is employed as the energizing means.

An object of my invention is to provide a controlled supply system for variable-load hydraulic multiple motors, which system is compact, self-contained, highly efficient and rugged, and which permits sensitive and accurate control of the motor at all times, under the most difficult and exacting operating conditions, which is of low first cost and which is entirely reliable under all extremes of operating conditions, even when handled by inexperienced operators.

Another object is to provide a system of the general type described, wherein is employed a constant speed, constant output hydraulic motor and wherein extreme flexibility of operation can be achieved at all times.

Other objects will in part be obvious and in part pointed out hereinafter, during the course of the following description.

My invention accordingly consists of the several parts, elements, and features of construction, and in the several operational steps, as well as in the relation of each of the same to one or more of the others, the scope of the application of all of which is set forth in the claims at the end of this specification.

In the drawings, wherein is disclosed one embodiment of my invention which I prefer at present,

Figure 1 comprises a schematic perspective view of the entire assembly;

Figure 2 is a fragmentary view of the mode and effect of throwing the control handle; while

Figure 3 is a graph showing the output shaft speed plotted against the oil flow through the system.

As conducive to a more thorough understanding of my invention, it may be noted at this time that considerable work has been directed towards the design of highly flexible hydraulic motor systems of small compass and low first cost. It has long been realized that in general, hydraulic systems are highly desirable for a variety of variable load uses, because of the high degree of flexibility inherent therein, their non-stalling characteristics under wide extremes of usage, and their inherent ruggedness even when subjected to considerable abuse and mishandling. Even greater flexibility is achieved where paired motors are employed, each of different characteristics, one being

2

adapted, to illustrate, for low-speed, high-torque duty, and the other for high speed, low-torque service. In a companion application entitled Hydraulic motor, filed June 15, 1945, Serial No. 599,679 (now abandoned), I have disclosed a multiple motor unit of this general type in which the drive components of the two motors are combined and impressed upon a common take off shaft. Such construction is not, however, essential to the proper operation of my present invention, and it is sufficient that two hydraulic motors be energized by such system, of either like or dissimilar characteristics.

Motors of this type, as just indicated, have wide fields of application. The recent technical advances brought about by the present World War have given rise to vastly broadened horizons in widely diversified fields of application. In turret controls on ships, tanks, etc., to illustrate, and particularly in land tanks, where the vehicles are moving rapidly over terrain which changes both in general and immediate contour throughout substantially the entire progress of the vehicle, a flexible motor control is required. It is further required that not only the motor, but as well, the energizing means and the control means be of small compass. As well, from a practical standpoint, they must be rugged and comparatively inexpensive both in first cost and in maintenance requirements.

At first thought, the simplest and most direct procedure would appear to be to provide some sort of variable output hydraulic pump connected directly to the multiple motors and supplying just the quantity of propelling fluid as is demanded from moment to moment. Difficulty is encountered, however, in that an adjustable output hydraulic pump of the type suggested is highly complicated and cumbersome, delicate, and necessarily expensive. Both in space requirements and in maintenance demands and its unreliability in the field, such a supplying unit is entirely impractical for mobile installations.

After considerable study directed to this problem, the thought occurred that perhaps satisfactory results could be obtained by utilizing the comparatively simple constant-speed, constant-output hydraulic pump of the non-pulsating, preferably rotary type, and to employ therefor a simple and rugged, self-contained control system which would meter required quantities of the fluid output of the pump to the associated motors in exact accordance with the instantaneous load requirements of the said motors.

One object of my invention, therefore, is to overcome the several defects, insufficiencies and disadvantages of the art as it has heretofore existed, and at the same time to provide a unitary, self-contained control system for effectively, reliably, and sensitively supplying multiple hydraulic motors from a constant-output hydraulic pump, and this with the low first cost and ruggedness and reliability in operation under all the rigors and abuses necessarily attendant upon field use, which will assure its acceptance in the industries.

Essentially, my new system comprises a constant-speed, constant-output hydraulic pump, and paired hydraulic motors, of either like or dissimilar characteristics, connected to each other across a suitable control unit including relief valves and metering valves.

Both the relief valves and the metering valves which constitute part of my control system, and both of which will later be described in substantially greater detail, are housed in a casing 10 common to them, and which may be of any suitable shape and dimensions. This casing is generally elongated and rectangular in section. I provide a cam shaft 11 extending longitudinally through casing 10 near the bottom thereof. This cam shaft is adapted for manual setting. The degree of movement thereof is relatively slow and slight, yet sensitive. To this end, it is important to mount the cam shaft in free acting bearings. Any suitable bearings may be used, and these are illustrated as comprised by suitable straps or carriers 12, 12 made fast to the casing 10 near opposite longitudinal ends thereof. These bearings may be of conventional anti-friction type, and it is entirely satisfactory that they be ordinary simple journal bearings, provided only that the shaft 11 can rotate therein without appreciable binding and without appreciable resistance at the first application of rotational force.

Before discussing in greater detail the features of construction of the several valves and their precise relation one to the other, it will first be helpful to examine the system in its entirety.

An oil reservoir 13 is provided at any desired point in the system. Physically, this may be in the same compartment or chamber as the rest of the equipment, or it may be placed in a separate compartment. It may be open or closed, as desired. While shown as open, convenience and caution dictate that in actual practice, this reservoir should be closed to prevent the influx into the system of water, dust or debris. A hydraulic pump 14 is provided, associated with reservoir 13 by a suitable suction pipe 14A.

An extremely important feature of my invention resides in this pump 14. This pump is of the constant-speed, constant-output type. At all times when in operation, and regardless of variations in load conditions, the output of this pump remains constant. This pump should be of a non-pulsating type and therefore, preferably a rotary pump. I find it convenient to use the multi-chambered hydraulic pump which is now so well known to the art under the trade name "Gerotor" pump. It is entirely feasible however, to use any other type of constant-speed, constant-output rotary hydraulic pump of proper rating. From pump 14, an outlet pressure lead 15 extends to the casing 10.

Since variable load conditions exist, it is necessary that control means be interposed between the pump 14 and the variable load which will

later be described. It is the controls within casing 10 which serve to fulfill this requirement. It is, of course, possible to install a pump of output which varies in accordance with the load requirements. Such a pump, however, as has been suggested, is both cumbersome and costly, and thus is highly impractical. I have evolved the present compact control assembly as a solution to this difficulty.

10 For the operation of the tank turret or other object to be energized by the two motors, I provide a low-speed, high-torque, heavy-duty motor 16 known as a tracking motor, and a comparatively high-speed, low-torque motor 17, which for convenience I term a slewing motor, disposed side by side on a suitable operating panel 18, all of which is shown schematically at the lower right of the figure. In a convenient and typical design the tracking motor has an approximately ten-to-one reduction ratio, while the motor 17 has an approximately one-to-one ratio.

20 The function of the tracking motor 16 is to bring the turret or other load into operation from its position of rest; whereupon, by suitable manipulation of the control handle, the slewing motor 17 is brought into operation and its driving component superimposed on that of the tracking motor 16 to permit the load to be brought at comparatively high speed to approximately its desired final position. At that point, the last fine adjustment is brought about by returning the control substantially to the tracking motor.

30 A more precise conception of the foregoing, and a more exact appreciation of how these two motors co-act, can perhaps best be obtained by reference to the graph constituting Figure 3. Therein output shaft speed is plotted as a function of the flow of energizing oil from the Gerotor pump 14. The units employed are of no consequence so long as they remain constant for the two functions. Two component curves are plotted, marked respectively tracking motor and slewing motor, and a "resultant" curve is compounded from these two component curves. At rest or zero position, indicated at 0, and corresponding to the neutral position of control handle 18A of the cam shaft 11, no oil flow takes place from the Gerotor 14 to the motors 16 and 17 and these latter are at rest. Oil from Gerotor 14 is by-passed directly back to reservoir 13. If now the control handle 18 is swung through a small angle from its rest position in either direction (and the curves are valid for either direction of motor rotation) some oil passes from Gerotor 14 through and to the motors. Let us assume that the control handle has been swung through about 3° to the right in Figure 2. Thereupon, a small part of the constant output oil from the Gerotor pump 14 is admitted to the tracking motor 16 through the control systems within casing 10, in a manner later to be described. Through the increase in oil flow from 40 0 through points A and B on the "resultant" curve in Figure 3, cam 51 does not lift the piston valve of secondary metering valve 46, all as later will be described. As a result, flow of working oil is solely to the tracking motor 16. This corresponds to the intermediate portion 0—A on the "resultant" curve. Thus, through the positions 0—A—B the "resultant" curve and the tracking motor curves are identical. Oil from the Gerotor 14 which does not reach the motor 16 during this stage of the operations is returned through suit-

able channels to the reservoir 13. While it has been suggested that 0—A in Figure 3 corresponds to a throttle opening of approximately 3° in the particular case undergoing description, more generally it might well constitute any intermediate throttle position.

As has been said, during this time oil is supplied only to the tracking motor 16. This latter operates at intermediate speed and intermediate torque. The motors 16 and 17 are geared to a common output shaft, in a manner constituting the subject matter of my said co-pending application. The details of this gearing do not per se form part of this invention, and are therefore omitted from this application.

Although oil is supplied only to tracking motor 16, throughout the range from 0—B on the "resultant" curve in Figure 3, more and more oil passes the control unit as control throttle 18A is brought further from its rest position, until the motor 16 is brought up to its maximum energy at B with full output from Gerotor pump 14 to this motor. This corresponds to slow speed operation of the motor unit at maximum torque. It further corresponds in a typical instance to an approximately 10° throw of the control handle 18A. Thus operating handle 18A is swung to permit increased oil flow when higher motor torque is required to compensate for increased load. Position B corresponds to the maximum load which can be handled by the motor assembly.

When it is desired to compound the action of the slewing motor 17 on that of the tracking motor 16, the control handle 18A is thrown still further in the desired direction. The control mechanism within the casing 10 then diverts in a manner which will be described, some of the oil pressured by the Gerotor pump 14, from the motor 16 to the motor 17.

It will be noted from the characteristic curve of the tracking motor 16 as shown in Figure 3 that while the first portion of this curve from 0 to B corresponds to the "resultant" curve, from point B on it displays a falling gradient. This is due to the fact that as more and more oil is supplied to the slewing motor 17, tracking motor 16 becomes progressively starved of energizing fluid.

The slewing motor 17, which comes into action at B, Figure 3, displays a steeply rising gradient. The output shaft speed thereupon rises sharply, due to the increased effect of the component of driving energy of the slewing motor upon increase in input fluid to that motor.

A torque curve would correspond roughly to the tracking motor curve, with maximum torque at B and with drooping characteristics beyond. By properly choosing the throttle setting, an output shaft speed can be selected which will provide optimum results for a particular load condition.

These characteristic curves of the two motors, properly identified in Figure 3, are algebraically superposed in the manner already suggested to produce the "resultant" curve characterizing the action of the motor unit. Consideration of this curve discloses that since oil flow from Gerotor 14 is a maximum at point B and cannot thereafter increase, then as the handle 18A is moved more and more to increase the diversion of oil to the slewing motor 17, necessarily less and less oil passes to motor 16. Finally a point is reached where substantially all of the oil is diverted from this motor, and the motor 16 is

carried substantially as an idler. When this condition is reached, the drive takes place substantially entirely through the one-to-one ratio of the slewing motor. The load is carried at the highest possible speed, but with relatively low torque.

Returning now to a discussion of the details of the control system, as illustrated in Figure 1, within the casing 10, I provide a primary cam-controlled metering valve 19. This valve comprises a valve housing 20, generally cylindrical in contour, in which reciprocates piston valve 21, made fast through a suitable opening in the bottom of the casing 20 to a piston rod 22. This piston rod 22 extends through a suitable sealing bushing (not shown) in the bottom of housing 20, and terminates at its outer extremity in cam follower 23 which engages and rides on the cam 24, made fast on the cam shaft 11. The bottom part or skirt of the valve element 21 is recessed transversely at 25 in the general shape of an inverted V. A coiled spring 26 of moderate pressure is disposed between the top surface of the piston valve 21 and the top of the casing 20, and serves normally to bias the piston valve gently in a downward direction. When the cam shaft 11 is in its neutral or rest position, the cam 24 is at its position of minimum throw. Spring 26 urges the piston 21 downwardly so that the follower 23 closely follows the cam 24. Portion 27 of inlet conduit 15 lets into the side of casing 20, the flow of pressure fluid therethrough, however, being normally blocked by the side walls of the piston valve 21.

Also provided within the casing 10 is a primary load-controlled relief valve indicated generally at 28. This valve 28 comprises a valve casing 29 and an inverted piston valve 30. Coiled spring 31 extends between the top 32 of casing 29 and the interior face 33 of the piston valve 30, the spring thus extending through the hollow skirt of the piston valve. This spring, along with the pressure of the metered fluid passing metering valve 19, exerts a downward force tending to bias the piston valve 30 towards the bottom of valve casing 29.

Keeping in mind that the Gerotor pump 14 is of the constant-speed, constant-output type, it will be seen that at all times when this pump is in operation there is a constant output of oil through the conduit 15. When this oil is blocked in portion 27 by the piston valve 21, it chooses whatever path is available. It passes through nipple 34 into the space 35 formed between the bottom of casing 29 and the working face 33 of piston valve 30. The pressure of the liquid passing through nipple 34 is sufficient to overcome the resistance of spring 31 and to maintain open the branched outlet pipe 36 which lets into valve casing 29 near the bottom thereof. At this time, the entire output of pump 14 flows from the outlet pipe 36 without appreciable resistance, through the main outlet pipe 37, to the reservoir 13.

If now, however, handle 18 be rotated a slight distance in either direction following the practice already developed in the discussion of the graph of Figure 3, say through an approximately 3° throw, the cam 24 is rocked so as to force the piston rod 22 of the metering valve 19 upwardly for a slight extent. The piston valve 21 is thereupon moved upwardly through a limited travel, against the tension of spring 26. This travel is sufficient for the opening 25, at least near its small-volume apex region, to come adjacent the portion 27 of the inlet pipe 15. Part of the con-

stant flow of oil from Gerotor 14 will pass through inlet pipe 15 and portion 27, to and through continuation 38 of the inlet pipe, disposed on the opposite side of the metering valve 20. Part of this pressure fluid which courses the metering valve 20 passes upwardly from inlet pipe 39 through branch pipe 39 and lets into the top of the relief valve 29, above the piston valve 30, exerting pressure thereon. The force of this pressure fluid is superposed on that exerted by the spring 31. Since the pressure of this fluid on the top of valve 30 tends to counter-balance that exerted by the fluid coming through branch pipe 34 to the other face of this piston, the force of the spring 31 is sufficient to move the piston valve 30 downwardly, to a certain extent, tending to block outlet pipe 36 at least partly, and under the control of the working fluid load. Flow between branch pipes 34 and 36 is thereby diminished in graduated amount.

A second secondary load-control relief valve is provided in the casing 10 and is indicated generally at 40. It has a generally cylindrical valve casing 41 housing an inverted piston valve 42. A coiled spring 43 is disposed between the top 44 of the valve casing 41 and the inner surface 45 of the piston valve 42. Spring 43 thus passes through the inverted hollow skirt of the piston valve and tends to bias the same downwardly.

It will be helpful at this point to consider the operation of the control unit when the system is first brought into operation. By no means all of the pressure fluid from the Gerotor 14 passes through the small opening provided by the apex portion of the opening 19 in piston valve 21, for the initial setting of cam 24. That portion of the pressure fluid which is not required for energizing the system in the manner now to be described is shorted, by means of primary relief valve 28, through branch pipes 34 and 36 to outlet pipe 37. Spring 31 of primary relief valve 28 does not completely close outlet pipe 36 at this time. Under these partial-load conditions fluid which undertakes to traverse pipe 38 is blocked at this setting of the cam shaft 11 which is undergoing description, by a second metering valve indicated generally at 46.

In a manner exactly similar to that already described with respect to metering valve 19, cylindrical valve casing 47 is provided for this valve 46, which casing 47 houses a hollow skirted piston valve 48, made fast to a piston rod 49. This piston rod 49 terminates in a cam follower 50 riding on the cam 51 fast on the cam shaft 11. A coiled spring 52 extends between the top surface 53 of the valve casing 47 and the top surface 54 of the piston valve 48. An inverted V-shaped opening 55 is provided in the under portion of the skirt of the piston valve 48. Since the walls of the piston valve 48 block the inlet pipe 38, the pressure fluid can flow only through branch pipe 56 to the space provided between the bottom of the casing 41 and bottom surface of the piston valve 42 of the secondary relief valve 40. From space 57 this pressure fluid flows through conduit 58 to a 4-way valve 59.

These 4-way valves are well-known to the art and are of conventional construction, and do not per se form part of this invention. Accordingly, the constructional details of these valves will be omitted. It is enough to say that I prefer these 4-way valves to be of the closed-center type, whereby all passages therethrough are blocked when the cam shaft 11 is in its neutral position. One 4-way valve is associated with each of the two

motors, and directs the pressure fluid to the associated motor in one direction or the other, according to the particular cam setting, to cause rotation of the motor in the desired direction. We will assume that the cam 60 on cam shaft 11 is so set for the illustrated instance, that its associated cam follower 61 and piston rod 62 actuate the 4-way valve 59 in such a manner and direction that flow takes place from conduit 58, through valve 59, and conduit 63 to the left side of the tracking motor 16. Return flow is from the tracking motor 16, through conduit 64, 4-way valve 59, branch conduit 65, and return conduit 31 to the reservoir 13.

As the handle 18A is swung more and more from its rest or neutral position, so that the cam shaft 11 is rocked through the range of say between 3° and 10°, the piston valve 21 is lifted more and more in the casing 20 of the primary metering valve 19. In the meanwhile, throughout this entire rotation of cam shaft 11, the opening 55 of the piston valve 48 remains closed against extension 38 of the inlet pipe. More and more pressure comes through pressure bleeder line 39 to the top side of primary relief valve 28. The piston 31 thereof finally is fully seated, thereby completely blocking outlet pipe 36. All of the constant output oil from Gerotor 14 is utilized and is passed to the tracking motor 16, so that the latter is operated at its high reduction ratio at full output and with highest degree of torque.

Upon slight further movement of the control handle 18A, opening 55 in the secondary metering valve 46 begins to open to the line 38. Part of the fluid from this inlet 38 courses across the secondary metering valve, and pressure is exerted from the branched pressure bleeder line 66 to the top of the secondary relief valve 40. Tending to counteract to a certain extent the pressure fluid from 38 and branch 56, the combined pressure of the fluid through conduit 66 and of the spring 43 forces the piston valve 42 slightly downwardly, blocking conduit 58 to a certain extent and cutting off some of the flow through this conduit from branch pipe 56. This diminishes slightly the flow to the tracking motor 16. Simultaneously, the fluid passing the secondary metering valve 46 courses through conduit 67 to the second 4-way metering valve 68, which is associated with the slewing motor 17. The mechanism of this valve 68 is operated through a piston rod 69 and associated cam follower 70, from cam 71 fast to the cam shaft 11. When metering valve 68 is opened and relief valve 40 is closed, part of the primary oil flows from conduit 67 through 4-way valve 68, pressure conduit 72, to slewing motor 17, and thence returns through return passage 73 to 4-way valve 68 and return conduit 37 to the reservoir 13.

Further movement of the operating handle 18A in the same direction causes the piston rod 49 to raise the piston valve 48 of the second metering valve 46 more and more, whereupon flow through passage 38 of the pressure fluid is uninterrupted by this opening. Full pressure from the Gerotor 14 is then imposed on the top side of the relief valve 40, eventually causing the complete seating of this valve and the unloading of supply to the tracking motor 16. At this time, all of the output of the pump 14 passes directly to the slewing motor 17 which carries the entire load, the motor 16 then being carried simply as an idler.

The foregoing description has been made on the assumption that the handle 18A is thrown in but

a single direction. Should the handle 18A be thrown in the opposite direction, however, then the functioning of the primary and secondary metering valves and primary and secondary relief valves remains the same as has already been described. Proper directioning of the energizing fluid to the motors is accomplished solely by the 4-way valves 59 and 68 and the cams 60 and 71, which correspond respectively to these two valves, and which are so contoured that the two motors 16 and 17, when simultaneously in operation, will always rotate in the same direction. We have just assumed a clockwise direction of rotation of the handle 18A, that is, to the left in Figure 1, so that the swing is to the right in Figure 2. We will now assume that the handle is thrown in the opposite direction, that is, to the right in Figure 1.

With this assumption, then with an approximately 3° throw, whereby flow takes place only through 4-way valve 59 from pressure conduit 58, then the flow of liquid may be traced through 4-way valve 59 down through conduit 64, through tracking motor 16, and back through conduit 63, 4-way valve 59, branch pipe 65, to return pipe 37. Upon further throw of the handle 18A in the same direction, the circuits just traced remain established but with slightly diminished flow so that the torque developed by the motor 16 drops off slightly, while at the same time a slewing-motor circuit is established through conduit 67, 4-way valve 68, down through conduit 73, to slewing motor 17, back through conduit 72, 4-way valve 68, and back to return conduit 37. Finally, when the handle 18A is thrown through the full extent of its throw to the right, secondary relief valve 40 discontinues flow to the 4-way valve 59, and all of the output of the pump 14 passes through primary and secondary metering valves 19 and 46 to the 4-way valve 68, and thence through conduits 73 and 72, to and from the slewing motor 17.

Where desired, brake control of the motors is had by way of valve 74. This is actuated by cam 75 on shaft 11 and cam follower 76. It controls the pressure of conduit 77 applied to the motor by way of conduit 78.

While the construction has been shown schematically and has spread out in development, it will of course be understood that in actual practice the unit is small, compact, and self-contained. It is extremely rugged and will perform satisfactorily under all extremes of operating conditions. My experience has shown that it is admirably equipped for tank turret control over the roughest terrain. Moreover, it is entirely suited for ship or aircraft turret control, or for general application where dual motors are required under widely dissimilar varying load conditions. Constant output pumps of extremely simple design and inexpensive production can be employed admirably with but simple regulatory equipment for widely varying load conditions. I have found that a Gerotor pump developing about 500-600 p. s. i. max. pressure will perform with entire satisfaction. Entirely suitable is the combination of a tracking motor with a 10-1 reduction ratio, operating at a maximum speed of about one-third that of a 1-1 ratio cooperating slewing motor. Wide acceptance in the art connotes and points to the essential advantages of my new construction.

As many possible embodiments may be made of my invention, and since many changes may be made in the embodiments hereinbefore set

forth, it will be understood that all matter described herein, or shown in the accompanying drawings, is to be interpreted as illustrative, and not in a limiting sense.

5 I claim as my invention:

1. As an element of a hydraulic control system wherein constant current uni-directional pressure fluid is utilized to energize paired hydraulic motors, a control unit for said motors comprising a manually-operated cam shaft and metering valves operating from said cam shaft, and connected with said motors and with said source of fluid supply so as, when the system is at rest, to return the entire fluid supply to a reservoir, and upon continued throw of the cam shaft, first to bring one motor into operation at full speed, and thereupon to provide differential supply of the energizing fluid to the paired motors.

2. As part of a multiple-motored hydraulic system, a control unit comprising means providing a constant unit volume of powering fluid, primary means for primarily metering a desired part of said powering fluid for transmission to the multiple motors, means for directing the remainder of said fluid back to a storage reservoir, secondary means for metering a desired part of the primary-metered fluid to one of said multiple motors, means for directing the remainder of said primary-metered fluid to the other motor, and means for regulating both said metering means.

3. As part of a multiple-motored hydraulic system, a control unit comprising means providing a constant unit volume of powering fluid, primary means for primarily metering a desired part of said powering fluid for transmission to the multiple motors, primary relief means for directing the remainder of said fluid back to a storage reservoir, secondary means for metering a desired part of the primary-metered fluid to one of said multiple motors, secondary relief means for directing the remainder of said primary-metered fluid to the other motor, means for regulating both said metering means to control the admittance of fluid therethrough, and means forming part of each said relief means and connected with the cooperating metering means for adjusting the outflow through said relief means.

4. As part of a multiple-motored hydraulic system, a control unit comprising means providing a constant unit volume of powering fluid, primary means for primarily metering a desired part of said powering fluid for transmission to the multiple motors, means for directing the remainder of said fluid back to a storage reservoir, secondary means for metering a desired part of the primary metered fluid to one of said multiple motors, means for directing the remainder of said primary-metered fluid to the other motor, and a single, manually-controlled means for regulating said metering means.

5. A control unit forming part of a multiple-motored hydraulic system, comprising, in combination, a source of constant-volume energizing fluid for operating said motors, regulatable primary metering means for directing a desired part of said energizing fluid to said motors, an associated primary relief means for bypassing the unused energizing fluid back to a system reservoir, a secondary regulatable metering means for directing a desired part of the primary fluid to one said motor, secondary relief means associated with said last-mentioned means for directing the remainder of the primary metered fluid to the other said motor, and means connected one with each said secondary means for respectively con-

trolling the direction of fluid supply to each said motor.

6. A control unit forming part of a multiple-motored hydraulic system, comprising, in combination, a source of constant volume energizing fluid for operating said motors, regulatable primary metering means for directing a desired part of said energizing fluid to said motors, an associated primary relief means for bypassing the unused energizing fluid back to a system reservoir, a secondary regulatable metering means for directing a desired part of the primary fluid to one said motor, secondary relief means associated with said last-mentioned metering means for directing the remainder of the primary metered fluid to the other said motor, means connected one with each said secondary means for respectively controlling the direction of fluid supply to each said motor, and means for regulating said metering means and said direction-determining means.

7. A control unit forming part of a multiple-motored hydraulic system, comprising, in combination, a source of constant-volume energizing fluid for operating said motor, regulatable primary metering means for directing a desired part of said energizing fluid to said motors, an associated primary relief means for bypassing the unused energizing fluid back to a system reservoir, a secondary regulatable metering means for directing a desired part of the primary fluid to one said motor, secondary relief means associated with said last-mentioned metering means for directing the remainder of the primary-metered fluid to the other said motor, means connected one with each said secondary means for respectively controlling the direction of fluid supply to each said motor, and manually-operated means common to, and for regulating said metering means and said direction-determining means.

8. A control unit forming part of a multiple-motored hydraulic system, comprising, in combination, means for supplying a constant unit output of energizing liquid, a regulatable primary metering valve for passing a desired part of said energizing liquid to said motors, a primary load-adjusted relief valve for bypassing the energizing fluid rejected by said primary metering valve back to a system reservoir, a regulatable second-

ary metering valve for metering a desired part of the primary-metered fluid to one said motor, a secondary load-adjusted relief valve for directing the remainder of said primary-metered fluid to the other said motor, and 4-way valves in circuit, one with each said secondary means, for determining the direction of flow of the energizing liquid to each said motor.

9. A control unit forming part of a multiple-motored hydraulic system, comprising, in combination, means for supplying a constant unit output of energizing liquid, a regulatable primary metering valve for passing a desired part of said energizing liquid to said motors, a primary load-adjusted relief valve for bypassing the energizing fluid rejected by said primary metering valve, a secondary metering valve for metering a desired part of the primary-metered fluid to one said motor, a secondary load-adjusted relief valve for directing the remainder of said primary-metered fluid to the other said motor, 4-way valves in circuit, one with each said secondary means, for determining the direction of flow of the energizing liquid to each said motor, a cam follower on each said metering valve and each said 4-way valve, a manually-operated cam shaft, and cams on said cam shaft cooperating with each said cam follower, for regulating the corresponding valves.

ALBERT RIVINGTON STONE.
